Primary Examiner — Mary Ann Calabrese*Assistant Examiner* — Katelin G Kloberg(74) Attorney, Agent, or Firm — Tommy SF Wang; Wang IP Law Group, P.C.(57) CLAIM

The ornamental design for a table, as shown and described.

DESCRIPTION

FIG. 1 is a perspective view of a table showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line portions of the table in FIGS. 1-7 represent unclaimed portions of the claimed design and form no part thereof.
